N. Y., assignors to American Car and Foundry
Company, New York, N. Y., a corporation of
New Jersey

Application July 30, 1942, Serial No. 452,934

3 Claims. (Cl. 294—67)

This invention relates to article lifters in general and in particular to a lifter for manufactured articles such as shells.

During the manufacture of shells and other symmetrical items various lifting arrangements are used but in most cases these are based on attachments to the shell, such as in the case or base. When the shell is nearly completed and prior to final inspection and painting it is necessary to thoroughly clean the shells by a degreasing operation. For this operation to be effective both the interior and exterior of the shell must be exposed as fully as possible to the fumes of the degreasing substance in order to speed production. It is also necessary that the plurality of shells be handled at one time and held in a definite predetermined position. It is an object, therefore, of the present invention to provide a shell or article lifter by which a plurality of shells or articles may be lifted and held in a predetermined spaced relation.

A further object of the invention is the provision of a shell or article lifter in which special pockets are provided contacting an extremely small area of the article to the end that the bulk of the article's surface may be exposed.

A still further object of the invention is the provision of a shell lifter of jointed construction which may be slid over the nose of the shells and lift the same in cantilever fashion from a horizontal to a vertical position during the lifting operation.

These and other objects of the invention will be apparent to persons skilled in the art from a study of the following description and accompanying drawings, in which

Figure 1 is an elevational view of the improved lifter with parts broken away to better disclose the construction;

Fig. 2 is an elevational view of the lifter when in shell receiving or shell discharging position;

Fig. 3 is a sectional view taken substantially on line 3—3 of Fig. 1, and

Fig. 4 is an elevational view showing the lifter in shell lifting position.

Referring now to the drawings in detail, it will be seen that the lifter consists of two main parts, namely, a top frame A and a bottom framework B hinged thereto. The top frame A is of truss formation having a top rod or tension member 2 and a bottom rod or compression member 4 joined together by struts 6 and diagonals 8. The top bar or rod has attached thereto a lifting eye 10 adapted to receive the hoist line by means of which the entire lifter may be raised.

A plurality of hinge straps 12 are fastened to the truss member and depend therefrom, as clearly shown in Fig. 1. The lower ends of these hinge straps are formed with openings or bearing portions adapted to receive the hinge pins by means of which the bottom framework B is connected to the top frame.

The bottom framework is formed by end straps 14 and intermediate rods 16. The intermediate rods 16 have hinge pins 18 attached thereto adjacent their upper ends and are joined together adjacent their lower end by connecting straps or bars 20. The bars 16 are additionally tied together by means of circular bands or rings 22 and by conical shaped cups or pockets 24 located adjacent the lower ends of the bars. These pockets or cup like structures are formed of sheet metal substantially conforming to the contour of the shell nose and have their upper edges reinforced by means of a narrow metal strip 26. In order that the shell nose may be fully exposed to the degreasing fumes a plurality of narrow strips 28 are welded on the interior of the conical shaped cup or pocket, thus these strips will hold the shell nose out of contact with the pocket walls and permit a full flow of the degreasing fumes over the shell nose. Short stays 30 connect the ring 22 and conical shaped pocket 24 in order to reinforce and prevent distortion of the ring or pocket. The straps 14 are, of course, fastened like the bars 16 to the ring 22 and conical shaped pocket 24.

It will be seen from the above that the bottom framework is pivoted to the top frame and may swing freely relative thereto. When it is desired to pick up a group of shells or similar articles the lifter is lowered toward the work table W, shown in Figs. 2 and 4, and the workman grasps the lower framework and pulls it toward the nose 40 of the shell. Continued lowering of the hoist and lifter will cause the lifter to pivot placing the upper and lower frameworks in the position shown by line and dash in Fig. 4. The workman then pushes the conical shaped pockets onto the nose of the shell and into the position shown by full lines in Fig. 4. In this position it will be noted that the pivot axis between the top and bottom frames is located adjacent the end or base 40 of the shell S, while the nose 42 is located wholly within the conical shaped pocket with the very tip of the nose, which is hollow, projecting slightly through the opening in the lower end of the conical shaped pocket. It will be seen that when the lifter is in the full line position of Fig. 4 the pivotal connection between the top and bot-

tom frames lies on one side of the center of gravity of the shell, while the conical shaped pocket lies on the opposite side. When the hoist is operated to raise the lifter the shells will accordingly be tilted by the pockets acting in cantilever fashion and finally picked up to assume the position shown in Fig. 1, after which they may be transported to the degreasing tank and from the tank to the receiving work table for deposit in exact order and in predetermined spaced relationship. When suspended, as shown in Fig. 1, the entire shell's outer surface is exposed to the degreasing fumes with the exception of the extremely small areas contacted by strips 28. The interior surface of the shell is, of course, fully exposed to the degreasing fumes since there is nothing projecting into the shell.

While the invention has been described more or less in detail, it will be obvious to persons skilled in the art that various modifications and rearrangements of parts other than those shown and described will suggest themselves and all such modifications and rearrangements of parts are contemplated as will fall within the scope of the appended claims defining our invention.

What is claimed is:

1. In a shell lifter the combination of a trussed top frame adapted to be connected to a hoist, straps depending from said trussed top frame, a bottom framework pivotally connected to said straps, upwardly open conical shaped pockets se-

cured to said bottom framework and forming a part thereof, said pockets being adapted to receive the nose portion of the shells and the pivotal connection of the straps and bottom framework being located adjacent the base of the shells when in position to be lifted, and spaced guides located in said pockets and adapted to contact the shell noses in limited areas.

5 2. In a shell lifter the combination of a top frame, and a bottom frame pivotally connected to said top frame and including spaced apart conical shaped pockets adapted to receive the nose portions of the shells to be lifted, and spaced ribs on the interior of said pockets and contacting small areas of the shell noses whereby the bulk 10 of the shell surface is free of contact with the lifter.

15 3. In a shell lifter, the combination of a trussed top frame adapted to be connected to a hoist, straps depending from said trussed top frame, a bottom frame pivotally connected to said straps, an upwardly open conical-shaped pocket secured to said bottom frame and forming a part thereof, said pocket being adapted to receive the nose portion of a shell to be lifted, and spaced ribs on the interior of said pocket and contacting a small area only of the nose of the shell 20 whereby the greater portion of the shell surface is free of contact with the lifter.
